UNITED STATES PATENT OFFICE.

EMIL MAURER, OF BERNE, SWITZERLAND.

DISH-WASHER.

1,124,318.

Specification of Letters Patent. Patented Jan. 12, 1915

Application filed August 27, 1912. Serial No. 717,262.

To all whom it may concern:

Be it known that I, EMIL MAURER, a citizen of the Swiss Confederation, and residing at Berne, Switzerland, have invented 5 certain new and useful Improvements in Dish-Washers, of which the following is a specification.

My invention relates to machines for rinsing utensils, crockery and the like, and a primary object is to provide such a machine 10 which comprises in a tank for holding rinsing water a journaled conveyer worm, a part of whose periphery projects into the water, and which is charged at its one end with the utensils to be cleaned which, when the worm rotates, pass along its turns, rotate in a direction opposite to the direction of rotation of the worm and then leave the latter at its other end.

One illustrative embodiment of my invention is represented by way of example in the accompanying drawing, wherein:—

Figure 1 is an elevation, a part being broken away, showing one construction of my improved machine, Fig. 2 is a longitudinal section through the same, Figs. 3 and 4 are detail views and, Fig. 5 shows other details.

Referring to the drawing, I arrange a 30 conveyer worm 4 on a rotatable shaft 3 journaled above a tank 1 which is rectangular in plan view; the said worm has a jacket formed by wires parallel to the shaft 3. The worm is inclosed by a cylindrical casing 2 whose lower half is rigidly connected or integral with the tank, while its upper half is detachable and constitutes a cover.

The turns or threads of the conveyer worm are constituted by spokes 5, preferably of wire, which, projecting radially from the shaft 3, connect together three concentric, spiral stays 6, 7 and 8, each of which consists preferably of light, flexible material, *e. g.* cane.

Each of the spokes 5 is connected with the three stays 6, 7 and 8, and the bases of all the spokes 5 on the shaft 3 are arranged in a spiral line. Between each two concentric turns of the stays 7 and 8 is attached, in addition, on each second spoke a cylindrical

brush 9 by means of a sleeve 10 pushed over the spoke. The shaft 3 traverses the one end wall of the casing 2 and carries on its projecting end, to which a crank-handle can be attached, a belt-pulley 12 and a sprocket wheel 13. The latter is connected by means of a chain 14 with a sprocket wheel 15 fast on a shaft 16. This shaft is journaled in a container 11 which is connected with the tank 1, is located outside the casing 2 and is parallel with the shaft 3, and carries a conveyer worm 17. At the end of the casing 2 away from the gearing 13, 14, 15 I provide at about the height of the shaft 3 an approximately rectangular aperture 18 (Fig. 6), adjacent to which is arranged a board 19 (Figs. 1 and 3). At the lower end of this board is a slide 20 (Figs. 3 and 4), whose motion is regulated by two screws arranged in slanting slots 22 in the slide. The slide is 70 under the influence of a spring 23 tending to press it against the periphery of a cam 24 fast on the shaft 3. Further, the casing 2 has in its side nearest the worm 17 an oval aperture 25 located near that end of the casing at which the chain gearing and crank-handle are provided. The aperture 25 is bounded by a shower pipe 26 which is connected to a hot water pipe 27. A pipe 28, connected by a branch 29 with the lowest 80 part of the tank 1, passes vertically through the bottom of the container 11 and enters into the lower half of the casing 2, the joint between this pipe and the bottom of the container being packed watertight. The pipe 28 is tapered conically below the branch 29; a rod 31, which exactly fits the conical end of the pipe 28, is provided with a handle 30, is hollow and is open at both ends shuts off the pipe 28 in the position shown in Fig. 2 from the branch 29 and simultaneously serves as overflow pipe for the tank. A drain pipe 32 is inserted into the lowest part of the container 11.

The illustrated machine is particularly adapted for rinsing flat utensils or crockery, such as plates.

The machine operates as follows: I will assume that the cam 24 is in the position shown in Fig. 4 and that the tank 1 is filled 10

with hot water. The water in the tank may be heated or kept warm by heaters 33 provided in the tank. In the said position of the cam 24 the slide 20 projects into the aperture 18 so that a plate placed with its hollow side downward on the board 19 abuts against the slide and cannot fall into the casing 2 and into the first turn of the worm 4. Now if the shaft 3 is rotated so that the cam 24 is rotated in the direction of the arrow shown in Fig. 4, the spring 23 shifts the slide 20 sidewise and downward, so that the plate on the board 19 can slide down the latter and fall into the first space between two turns of the worm 4. On the shaft 3 being rotated farther the slide 20 is lifted and only lowered again when the worm 4 has rotated one complete revolution. A second plate placed in the meantime on the board 19 can then fall into the end of the worm, while the first plate is now in the second space between two turns. In this manner the plates to be cleaned are individually inserted into the machine which prevents the plates being broken without impairing the speed of the operation, as the worm can be kept in constant rotation.

The plates located in the lower part of the worm projecting into the water are constantly rotated in a direction opposite to the direction of rotation of the worm, as indicated by the arrows in Fig. 5. Consequently, all parts of the plates come into contact with the rinsing water. In addition, they are brushed by the brushes 11, and even when plates of various diameter are being rinsed each part of the same is repeatedly brushed when passing along the worm in consequence of the plates rotating when care is taken that the brushes are broad enough to brush the plates beyond their centers. When one plate has traveled entirely through the worm 4 it is met by a pin 34 provided on a strip 35 (Fig. 2) attached to the end of the last turn of the worm, is lifted out of the water and conveyed through the aperture 25 of the casing 2 onto the one end of the worm 17. When passing through the aperture 25 each plate is liberated from rinsing water adhering to it by hot water issuing from the shower pipe 26, and the plate which is otherwise heated by the rinsing water is raised to such a temperature that it arrives almost dry at the other end of the worm 17. The diameter of the worm 17 is so small and the clearance between it and the casing 2 and the adjacent end wall of the container 11 is so small that the plates cannot fall down into the lower part of the container, but lying against the shaft 16 and against a journaled rod 36 running along one of the walls of the container 11 can be conveyed by the worm 17 to the other end. The end wall of the container 11 opposite this end of the worm has an aperture 37 limited above by a strip 38. When the plates issue from the worm 17 they abut against this strip and slide with their hollow sides upward onto a shelf 39 (Fig. 1) projecting outside the container 11 below the aperture 37, from which they can be removed. After the rinsing is finished the water is run out of the tank by lifting the rod 31, the residues of food collected at the bottom of the tank, or like substances, being for the most part washed away. Water which drops from the washed plates collects at the bottom of the container 11 and runs away through the pipe 32.

As the brushes are worn away rather rapidly in hot water, *i. e.* as the bristles or roots of which the brushes are made are readily bent, the sleeves 10, carrying the brushes, must be rotated slightly from time to time, this being done by hand without difficulty; care must, however, be taken that the sleeves 10 are not so loose on the spokes 5 that they automatically rotate during the rinsing operation.

I claim:—

1. A dish-washer having a rinsing-water tank; a conveyer-worm in which are mounted brushes and the worm-threads of which are pervious to water, and a foraminated covering for said conveyer-worm; the space between the latter and its covering being of sufficient size to receive the dish, which is set in rotation during its travel along the worm.
2. In a rinsing-machine, the combination with a tank containing water, of a conveyer worm journaled in the tank and having part of each turn in the water in the tank, and a perforated jacket on the worm, the turns of the worm being perforated.
3. In a rinsing-machine, the combination of a casing a part of which constitutes a tank, a conveyer worm journaled in the casing and having part of each turn in the tank, said casing having an inlet at one end of the worm and an outlet at the other end; a board sloping down to the inlet, a spring-influenced slide normally lying below the edge of the board at the inlet, and means actuated by the worm for moving the slide to a position above the edge of the board.
4. In a rinsing-machine, the combination with a tank containing water, of a conveyer worm journaled in the tank and having part of each turn in the water in the tank, and a plurality of brushes journaled in the walls of the thread of the worm, said walls being pervious to water.
5. In a rinsing-machine, the combination of a casing a part of which constitutes a tank, a conveyer worm journaled in the casing and having part of each turn in the tank, said casing having an inlet at one end of

the worm and an outlet at the other end; a container parallel to the casing, a conveyer worm journaled in the container, means on the former worm for lifting a utensil 5 through the outlet to one end of the latter worm, and a shelf on the container at the other end of the latter worm.

In testimony whereof, I affix my signature in the presence of two witnesses.

EMIL MAURER.
